UNITED STATES PATENT OFFICE.

HENRY L. BULLEN, OF NEWARK, NEW JERSEY, ASSIGNOR TO AMERICAN TYPE FOUNDERS COMPANY, OF JERSEY CITY, NEW JERSEY, A CORPORATION OF NEW JERSEY.

PRINTER'S CABINET.

1,283,655.

Specification of Letters Patent.

Patented Nov. 5, 1918.

Application filed August 21, 1915, Serial No. 46,719. Renewed July 8, 1918. Serial No. 243,964.

To all whom it may concern:

Be it known that I, HENRY L. BULLEN, a citizen of the United States, residing at Newark, Essex county, and State of New Jersey have invented and discovered certain new and useful Improvements in Printers' Cabinets, of which the following is a specification.

In printing establishments of common arrangement, much time is wasted by compositors in obtaining the type and spacing elements necessary in setting up ordinary forms of printed matter, due not only to the unscientific arrangement of the work-cabinets in relation to the facilities for storing the type and spacing elements, but likewise to the unscientific arrangement and construction of the cabinets themselves, in which such type and spacing elements are stored and arranged for use.

My present invention relates to printing office furniture and particularly to tops for compositors' work-cabinets, consisting chiefly in a system for the arrangement of the compartments for containing spaces, quads, leads, slugs, etc., and in the combinations, assembly and form thereof, as will be herein-after more fully described and claimed.

The purpose of the invention is to provide a cabinet with a compositors' work-bank with case, or cases and racks, adapted, when arranged in alley formation, not only to give ample working room to the compositors and place within their convenient reach the necessary supply of type and a complete and proper assortment of spacing materials, but to have such type and spacing materials arranged in relative quantities and position, one assortment to another, so that the compositor will have a complete supply of each assortment for a given amount of work, the supply of one assortment being comparatively equal to the supply of every other assortment in a given quantity of work of average character. A further purpose is to provide compartments in such work-bank of a form adapted to contain the spacing elements in a position easily seized and removed by the hand of the compositor. This and other details of construction and arrangement of parts serve to increase the general efficiency and productive capacity of each compositor and effect a saving of expense and time in the operation of a composing room.

In the accompanying drawings:

Figure 1 is a perspective view of a compositor's work-cabinet having the improved form of top,

Fig. 2 a detail perspective view of the spacing materials case, removed from the top,

Fig. 3 a transverse sectional view on the line 3—3 of Fig. 2 and showing the inclined bottoms.

Fig. 4 a sectional view taken on the line 4—4 of Fig. 2, showing the rounded bottoms, and

Fig. 5 is a sectional view of a single compartment taken on the line 5—5 of Fig. 4, showing the rounded bottoms.

Referring to the construction in further detail, the cabinet, which may be of sheet metal or wood, consists of the ordinary frame comprising end members 1 and 2, base 3, and a middle member 4 receiving the type drawers 5 arranged in two tiers.

The cabinet top is constructed of a pair of end pieces 6 and 7, having a bottom 8, suitably secured to the frame and having shelves 9 and 10 forming the working bank, and a shelf 11 on the "case" side supporting a removable spacing materials case or cases 12. A plurality of partitions 13 are arranged between the shelf 11 and the bottom 8 to receive leads and slugs in lengths from ten to fifty picas each, graduated by ems.

The spacing materials case illustrated in Figs. 2 to 5 comprises a tray 12 divided by strips 14 and 15 into three sections 16, 17 and 18. The section 16 is divided and subdivided by strips 19 into compartments for holding spaces and quads of eight or more different sizes, of approximately sixteen pounds of each size. The compartments are of such size and so arranged that a complete supply of each assortment of spaces and quads is available, i. e., the supply of one assortment will be relatively equal to the supply of every other assortment, and the sizes of spaces and quads most used are located to be the easiest reached by the compositor. The section 17 has a main dividing strip 20 and subdividing strips 21, forming the upper and lower divisions of compartments to contain copper thin and one-point brass spaces. Said compartments are arranged in four rows of eight or more compartments in each row, and each compartment is constructed with a rounded bottom 110

22 and perpendicular walls 23, thereby making it easy to pick out the smallest and thinnest space without the slightest difficulty. Much time is lost in extracting copper thin 5 spaces from the present used square bottom boxes.

The case section 18 has subdividing strips 24 forming compartments to contain metal spaces of different points, and double depth 10 compartments for leads and slugs of different lengths, graduated by pica ems. These compartments have inclined bottoms 25, which prevent the leads or slugs from being wedged, and to enable the leads to be picked 15 out with the fingers without difficulty when the compartments are filled. The compartments 24 are adapted to contain leads and slugs from one and one-half to nine and one-half ems, and the rack 13 is adapted to hold 20 lengths of leads from ten to forty picas and slugs from ten to fifty picas, graduated by ems.

The top may be constructed as a separate article adapted for use on two full-sized flat 25 top cabinets of the proper height, or on cabinets and case stands with bracket tops, or in fact, on any cabinet of standard height which has a removable top.

It is obvious that those skilled in the art 30 may vary the details of construction and arrangement of parts without departing from the spirit of the invention, and therefore I do not wish to be limited to such features except as may be required by the claims.

35 Having thus fully described my said invention, what I claim as new and desire to secure by Letters Patent, is:

1. A spacing materials case for printers' use comprising a tray, a plurality of trans-

versely crossing strips secured in the tray 40 and providing compartments to receive the assortment of spacing material, said compartments being disposed and of the relative size to hold a complete and proper assortment of spacing materials whereby each assortment will be comparatively equal to the supply of every other assortment, said compartments having integral and inclined bottoms whereby to facilitate removal of the spacing members, substantially as set forth. 50

2. A spacing materials case for printers' use comprising a tray, a plurality of transversely crossing strips secured in the tray and providing compartments to receive the assortment of spacing material, said compartments having rounded bottoms and perpendicular walls whereby to facilitate removal of the spacing members, substantially as set forth. 55

3. A spacing materials case for printers' use comprising a tray, a plurality of transversely crossing strips secured in the tray and providing compartments to receive the assortment of spacing material, certain of said compartments having inclined bottoms 65 and others of said compartments having rounded bottoms and perpendicular walls whereby to facilitate removal of the spacing members, substantially as set forth. 60

In witness whereof, I have hereunto set 70 my hand and seal at Newark, New Jersey, this 18th day of August, A. D. nineteen hundred and fifteen.

HENRY L. BULLEN. [L.S.]
